UNITED STATES PATENT OFFICE

GUSTAVE HILDING ANDERSON, OF NEW BRITAIN, CONNECTICUT, ASSIGNOR TO THE HART & HUTCHINSON COMPANY, OF NEW BRITAIN, CONNECTICUT, A CORPORATION OF CONNECTICUT

GRAVITY HINGE

Application filed September 23, 1926. Serial No. 137,220.

This invention relates to hinges, and more particularly to a gravity hinge which will normally retain a door in closed position and will return it to closed position 5 after it has been opened in either direction.

The objects of this invention are to provide a gravity hinge of the above nature which will be simple in construction, inexpensive to manufacture, easy to install and 10 manipulate, ornamental in appearance, and very efficient and durable in use.

With these and other objects in view, there has been illustrated on the accompanying drawing one form in which the invention 15 may be conveniently embodied in practice.

Fig. 1 represents a front view, partly in section, of the gravity hinge, together with portions of a door and door post to which the hinge is attached.

20 Fig. 2 is an edge view of the same.

Fig. 3 is a front view of the complete door and door post showing the gravity hinge applied thereto.

Referring now to the drawings in which 25 like reference numerals denote corresponding parts throughout the several views, the numeral 10 indicates a swinging door which is adapted to be rotatably connected to a door post 11 by means of an upper simple hinge 12 and a lower gravity hinge 13. The hinges 12 and 13 are provided with angular brackets 14 and 15 which have vertical arms adapted to be secured to the post 11, as by screws 16. The horizontal arms of the 30 brackets 14 and 15 are provided with vertical apertures 17, one of which is clearly shown in Fig. 1. The top of the door 10 is provided near its inner edge with a vertical pintle 18, which is adapted to fit loosely within the aperture 17 of the upper bracket 14, whereby said pintle 18 will be permitted 35 to slide freely up and down as the door opens and closes.

40 The gravity hinge 13 is provided with a stepped shaft 19 located within and rigidly supported by the horizontal arm of the lower bracket 15. The stepped shaft 19 has three cylindrical sections 19^a, 20, and 21, the former having the smallest and the latter 45 the largest diameter. The cylindrical sec-

tion 19^a of the shaft 19 is adapted to fit within the aperture 17 in the lower bracket 15 so that the shoulder formed between the stepped sections 19^a and 20 of the shaft will rest upon the top of the horizontal arm of the angular bracket 15. The bottom of the shaft 19 is threaded at 22 to receive a nut 23 which serves to rigidly hold said shaft in any desired adjusted position. 55

For convenience in manipulating the shaft 60 when it is desired to twist it to a new adjusted position, the intermediate portion of the shaft 19 is provided with a pair of parallel flat sides 24 and 25 adapted to be engaged by a wrench or other tool. 65

The top section 21 of the stepped shaft 19 is provided with an inclined face 25^a from which extends a pintle 26, said pintle having its base lying partly within and partly without the body of the enlarged section 21 and being provided with a shoulder 26^a. Surrounding the pintle 26 is a ball-bearing raceway comprising an inner annulus 27 and an outer annulus 28. The inner annulus 27 is tightly fitted upon the inclined pintle 26, 70 while the outer annulus 28 is rotatably mounted with respect to said inner annulus by means of a series of anti-friction balls 29. 75

In order to movably support the door 10 upon the stepped shaft 19, said door is provided on the inner end of its lower edge with a bracket 30, said bracket being secured to said door, as by a screw 31. The bracket 30 is provided with a tubular depending skirt section 32 surrounding the upper portion 21 of the stepped shaft 19, whereby dust or other injurious material will be prevented 80 from entering the interior of the gravity hinge 13. 85

The bracket 30 is provided at its upper 90 end with a pair of oppositely beveled flat sections 33 and 34 which are adapted to embrace opposite sides of the lower edge of the door 10.

In order to support the bracket 30 upon the stationary part of the gravity hinge, provision is made of a slightly rounded, wedge-shaped knife edge 35, said knife edge having an upper rectangular section 36, which is secured, as by a crew 37, to the 100

front of the skirt section 32. The wedge member 35 is adapted to lie in contact at all times with the outer annulus 28, and to normally rest at the lowermost section 5 thereof when the door is in closed condition.

In operation, when the door is swung open in either direction, the bracket 30 together with the wedge member 35 will turn about the pintle 26 carrying the outer annulus 28 with it. During this movement, the outer annulus 28 will rotate with respect to the inner annulus 27, elevating the bracket 30 to a position depending upon the angle to which the door has been opened. When the door is released, the weight thereof will cause the knife edge to travel down again until the door reaches its normal closed position.

While there has been disclosed in this specification one form in which the invention may be embodied, it is to be understood that this form is shown for the purpose of illustration only, and that the invention is not to be limited to the specific disclosure but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a gravity hinge, a bracket member adapted to be secured to a door, a second bracket member adapted to be rigidly secured to a door post, an inclined pintle on said second bracket, an annular ball-bearing raceway on said pintle, and means on said first bracket for engaging the lower edge of said raceway whereby said door will return by gravity to closed position after being opened.

2. In a gravity hinge, an inclined pintle adapted to be fixedly secured to a door post, an anti-friction member mounted to rotate on said pintle, a bracket secured to the bottom of a door, said bracket having a tubular depending skirt section surrounding said inclined pintle, and a wedge-shaped member engaging said anti-friction member and adapted to raise the door when it is swung in either direction, said door being adapted to be returned by gravity to its normal closed position after being opened.

3. In a gravity hinge, an inclined pintle adapted to be fixedly secured to a door post, an anti-friction member mounted to rotate on said pintle, a bracket secured to the bottom of a door, said bracket having a tubular depending skirt section surrounding said inclined pintle, and a knife edge carried by said tubular depending section for engaging said anti-friction member and adapted to raise the door when it is swung in either direction, said door being adapted to be re-

turned by gravity to its normal closed position after being opened.

4. In a gravity hinge, a bracket adapted to be attached to a door post, a stepped shaft having its lower end fitting within said bracket, an inclined pintle on the top of said shaft, an annular anti-friction member rotatably mounted on said pintle, means secured to a door for engaging the lower portion of said anti-friction member and adapted to move up around said pintle to raise the door when it is swung in either direction, said door being adapted to return by gravity to its normal closed position after being opened.

5. In a gravity hinge, a bracket adapted to be attached to a door post, a stepped shaft having its lower end fitting within said bracket, an inclined pintle on the top of said shaft, an annular anti-friction member rotatably mounted on said pintle, and a wedge-shaped member engaging said anti-friction member and adapted to raise the door when it is swung in either direction, said door being adapted to be returned by gravity to its normal closed position after being opened.

6. In a gravity hinge, a bracket adapted to be attached to a door post, a stepped shaft having its lower end fitting within said bracket, an inclined pintle on the top of said shaft, an annular member rotatably mounted on said pintle, ball-bearing anti-friction means mounted on the top of said shaft and surrounding said pintle, and a wedge-shaped member engaging said anti-friction means and adapted to raise the door when it is swung in either direction, said door being adapted to be returned by gravity to its normal closed position after being opened.

7. In a gravity hinge, an inclined pintle adapted to be fixedly secured to a door post, an anti-friction member mounted to rotate on said pintle, a bracket secured to the bottom of a door, and a wedge-shaped member engaging said anti-friction member and adapted to raise the door when it is swung in either direction, said door being adapted to be returned by gravity to its normal closed position after being opened.

8. In a gravity hinge, an inclined pintle adapted to be fixedly secured to a door post, a bearing member mounted to rotate on said pintle, a bracket secured to the bottom of a door, and a wedge-shaped member engaging said member and adapted to raise the door when it is swung in either direction, said door being adapted to be returned by gravity to its normal closed position after being opened.

9. In a gravity hinge, a bracket adapted to be attached to a door support, a shaft supported by said bracket, an annular anti-friction member rotatably mounted on an

inclined axis on said shaft, a wedge member secured to a door resting upon said anti-friction member and adapted to move upwardly to raise the door when the door is 5 swung in either direction, said door being adapted to return by gravity to its original position after being opened.

In testimony whereof, I have affixed my signature to this specification.
